UNITED STATES PATENT OFFICE.

WILLIAM JAMES PARSONS, OF LONDON, ENGLAND.

APPLIANCE FOR PLAYING RACE GAMES.

1,414,788.

Specification of Letters Patent. Patented May 2, 1922.

Application filed February 1, 1922. Serial No. 533,457.

To all whom it may concern:

Be it known that I, WILLIAM JAMES PARSONS, a subject of the King of Great Britain, residing at London, England, have invented 5 certain new and useful Improvements in Appliances for Playing Race Games, (for which I have filed an application in England November 25, 1920,) of which the following is a specification.

10 This invention relates to an improved race game, of the type in which playing pieces such as toy horses are moved over a chart, representing a race course, according to certain rules, and as determined by cards bearing indications corresponding to the playing pieces and also instructions, denoting the moves to be imparted to the various playing pieces by the players.

15 The object of the invention is to provide a race game which can be played under conditions closely approaching those introduced in actual racing, such as in flat, hurdle, or steeplechasing.

According to the invention, the moves to 20 be made by toy horses over a base or board marked out to represent a race course are controlled by means of a pack of cards, bearing 25 indications corresponding to the horses and also instructions as to the nature of the move 30 to be made by the horse or horses, the instructions being such however, as not only to provide for simple forward moves, but also to provide for bumping, swerving, bettering of position by moving nearer to the rails of the 35 course and the like, moves corresponding to conditions arising in actual racing.

The invention also includes the use of a 40 movable model winning post, and the addition to the pack of cards, of a "winning post" card, for a purpose to be hereinafter more fully described.

The invention further includes the use of 45 miniature hurdles with corresponding "fall" cards added to the pack.

50 In order that the invention may be more readily understood, reference will now be made to the accompanying drawings, which illustrate the various elements utilized in playing the game, and in which drawings;

Figure 1 is a plan view of the base with the course marked out thereon.

Figure 2 represents one set of cards for one horse, and forming part of a pack.

Figure 3 represents one set of cards for a pair of horses, and also forming part of the 55 pack.

Figure 4 is a plan view of a model movable winning post.

Figures 5 and 6 are respectively a plan and side view of a model hurdle and 60

Figure 7 represents one of the horses.

In carrying out the invention according to one mode by way of example, in its application to a horse racing game for eight players, a flat base which may be constructed of 65 wood, but preferably made of linen so as to permit of folding or rolling, is marked out in the form of a course in the following manner.

Two spaced parallel lines 2, 2, are provided 70 to represent side rails of the course, and such side lines 2, 2, are joined at their upper and lower ends by the lines 3, 4 respectively to form a rectangle.

The side lines 2, 2, are joined near to each 75 end by the cross lines 5, 6, of which constitute the starting line and the winning line respectively.

The space between the line 4 and the line 5, is divided into eight spaces 8 by lines 80 7 parallel to the side lines 2, 2, each space 8 being provided for a horse and advantageously corresponding in length thereto.

Aligned with each space 8, and extending the full length of the course, is a track 85 constituted by short longitudinally spaced lines 9 at right angles to the side lines 2, one track thus being provided for each horse.

The distance between the lines 9 of each track is the same up to the line A—B which 90 is arranged at a point about three quarters of the length of the course, and from this point the distance is lessened.

The lines 9 of the first, third, fifth and 95 seventh track are displaced longitudinally relatively to the lines 9, of the second, fourth, sixth and eighth track, as shown.

Certain of the tracks may be marked with 100 rings 10, and a distance line 11 may be marked at a point near to the winning line 6.

A line of dots 12 divides the course centrally and longitudinally.

Model horses 13 such as shown in Figure 7 a winning post 14, Figure 4, and a pack of cards are provided for use with the base.

5 The pack of cards comprises one set of four for each horse and one set of four for each successive pair of horses.

10 The four cards constituting the set for horse No. 1, are shown in Figure 2, from which it will be seen that all four cards are marked with the number of the horse, and bear respectively the following instructions.

- (a) Moves four spaces.
- (b) Moves three spaces.
- (c) Moves to rails and one forward.
- 15 (d) Bumped, rest move one forward.

20 It is of course to be understood that four similar cards bearing the same instructions but marked with different numbers corresponding to different horses are provided for each of the other horses.

25 The four cards constituting a set for a pair of horses are marked with the numbers of the horses forming the pair, two of the cards having the lower number first, and the other two having the lower number last, as shown in Figure 3 which represent the set for horses No. 1 and 2. Each horse of the pair thus has an equal chance of precedence as regards "turn," or order of move.

30 In addition to the numbers of the horses arranged as described, the cards constituting this set bear the following instructions respectively as shown in the figures in question

- 35 (a) Nos. 1 and 2 move 1 space.
- (b) Nos. 2 and 1 move 1 space.
- (c) {No. 1 moves two spaces.
- (d) {No. 2 moves two spaces.

40 As before it is to be understood that sets of cards bearing the same instructions are provided for horses 3 and 4, 5 and 6, and 7 and 8.

45 In playing the game the numbered horses are arranged in the spaces 8, which may be correspondingly numbered and the cards are either turned up successively, and the moves made by the players, according to the instructions on the card turned up, or the cards 50 may be dealt out to the players, who then either turn them up successively, in order of play, without first inspecting them, or first inspect them, and play them according to their judgment, and in turn, as in whist for example, the horses being moved in every case by the players in accordance with the instructions given on the cards turned up or played.

55 60 Thus for example, if a card bearing the number 1 with the instructions "Moves three spaces", is turned up, or played, the player owning horse No. 1 moves his horse from the space 8, on to the third line 9 of the track for that particular horse.

Similarly the other players move their horses from the spaces 8 on to their respective tracks as the cards are turned up or played, giving instructions for the particular moves.

70 If a card bearing for example, the number 1 with the instructions "Bumped rest move one forward", the player owning horse No. 1 moves his horse forward, but diagonally to the next line 9, in a direction towards the dotted centre line 12, which move in effect brings that horse only half a space nearer to the winning post, but on the track for another horse, whilst all the other players move their horses on to the next line 9, of 80 their own tracks if not already taken up by another horse.

When a card is turned up or played bearing the instructions "No. 2 moves two spaces, No. 1 swerves" the player owning 85 horse No. 2 moves his horse forward from the line 9, on which the forefeet of the horse are then engaged, on the second line 9, therefrom, while the player owning horse No. 1 moves his horse forward, but diagonally to 90 the second line 9, away from the line originally occupied, this move in effect placing that horse one space nearer the winning post.

Should for example, the card be played or turned up bearing the number 1 and the instructions "Moves to rails and one forward" 95 the owner of horse No. 1 first moves his horse laterally until reaching one of the side rails 2 and then forwardly to the next line 9.

If the horse of a player in making a move 100 is passed over a space marked with the ring 10, the space is not counted, but if a horse by being "bumped" or "swerving" reaches a space marked with a ring 10, such space must be counted as usual.

105 By making the distance between the lines 9 shorter towards the winning post line the progression of the horses is delayed thereby adding to the chances of the horses finishing level or in close relation, and so denoting 110 small degrees by which the foremost horse wins.

115 Each horse is advantageously of a length equal to two spaces between the lines 9. Again, as the lines 9 are in staggered relation, one horse may arrive at the winning post say half a division in front of the next and so on, and such amount may be considered as winning by a neck.

120 From the foregoing the manner in which the moves are to be made in accordance with the instructions on the cards will be readily appreciated.

Observance of the following rules, which are given by way of example, will facilitate 125 play in its simplest form.

(1) All horses at the start to be placed in their respective spaces, (which may be drawn for) with forefeet on the starting post line (5).

(2) The cards to be dealt out to the players, or exposed successively by a referee.

(3) Horses to be moved in accordance with the instructions on the cards as they are exposed or played, by sliding said horses from one position to another as the case may be.

(a) Directly forward.

10 (b) Diagonally as necessary, or if preferred to directly forward.

(c) Sideways.

(4) After crossing the starting post line both forefeet of each horse to be always on a stop (i. e. a line 9), two horses not being 15 permitted in the same space at the same time.

(5) No horse to be permitted to occupy the space immediately in front of another horse unless "bumped" or "swerved" into 20 that position, although a space immediately behind a horse may be occupied by the horse of another player.

(6) Any move prevented from completion by reason of the position taken up by 25 one or more horses on the course, to be completed as far as possible.

(7) All horses to be moved in the order in which their numbers appear on the cards.

(8) In moving a horse over a ringed space, 30 the space is not to be counted, but a horse being "bumped" or "swerved" on to a ringed space, to count that space as usual.

(9) "Bumped" or "swerved" moves to be taken "away from" the nearer rails, even 35 if the latter move is only partly possible, if not possible at all in this direction, the move to be taken towards the near rails.

These moves may occur at any position, 40 on the course and a horse may be "bumped" or "swerved" over the winning post, and thus win. If a horse is "bumped" or "swerved" at the starting post line however, the move is to be lost.

(10) When the card is played or turned 45 up bearing the instructions "Rest move one" the leading horse is to be moved first and so on in order. If two horses are level the horse nearer the No. 1 side of the course to have first move of the two. This move is 50 not to be allowed to any horse beyond the distance line.

(11) A horse "moving to rails" to have 55 the choice of (1) either direction (2) moving only partly towards the rails (3) not moving sideways at all, the move forward however is always to be taken.

(12) The first horse having its forefeet placed beyond the winning post line is the 60 winner.

(13) A dead heat occurs only when two horses are both on the winning post line and a card is exposed giving instructions for both to move one space.

(14) When two horses are both on the 65 winning post line, and a card is exposed

instructing one to move two spaces, and the other to swerve, the former is the winner, and the latter is to be regarded as second.

The course may be provided at suitable and advantageously equally spaced distances 70 with marks 15, 16 denoting the positions at which model hurdles 17 as shown in Figures 5 and 6 may be arranged, and in such case a set of cards one card for each horse, bearing the number of the horse, and the instruction "Fall" should be added to the pack. 75

The game then proceeds in the same manner as before described, but in passing over a hurdle the forefeet of the horses should be placed immediately above the line 9 upon 80 which they should ordinarily be resting if the hurdle were omitted.

A horse on passing a hurdle may "rest" in four different positions viz:

(1) With the forefeet just touching the 85 top of the hurdle.

(2) With its forefeet well over the hurdle.

(3) Resting on the hurdle slightly more than half way over and

(4) With the lower part of its rear legs 90 resting on the hurdle.

Should a card be turned up or played bearing the instruction "Fall" then the horse denoted by that card, if said horse is in any of the four positions last mentioned, remains 95 there until all other horses behind have been passed over, or remain on the hurdle.

In either variation of the games i. e. with or without hurdles, a card marked "Winning post" and bearing an instruction to move the 100 winning post into another position may be added to the pack, and the game then proceeds as before, except that if the "Winning post" card be turned up or played the movable winning post 14 is placed on the course 105 in the position indicated by the card.

The game then continues, with the post 14 in its new position, taking the place of the winning post line 6, on the track.

Instead of using model hurdles, the course 110 may be marked by lines for example and indications to denote hurdles, and similarly indications such as "Starting post" "Distance line" and "Winning post" may be marked on the course.

115 It will be readily appreciated from the foregoing that many variations may be made in the method of play without departing from the invention, and it is therefore to be understood that the invention is in no way 120 limited to the methods of play given by way of example.

I claim:

1. In an apparatus for playing race games, including playing pieces representing 125 horses, a chart marked in the form of a race course upon which said horses are moved in the playing of the game, and a pack of cards bearing indications for the moves of the horses upon said chart, said cards in. 130

cluding sets of cards limited to each particular horse and sets of cards limited to certain pairs of horses, whereby a single card may control the movement of a single horse or a 5 pair of horses.

2. Apparatus for playing race games comprising in combination playing pieces representing horses, a pack of cards bearing indications corresponding to the horses and 10 instructions for the moves to be made by the particular horses indicated some of said cards also bearing penalty and privilege indications simulating the conditions encountered in actual racing such as bumping, 15 swerving, proximity to the rails, and the like, one card in said pack bearing an indication denoting the position of the winning post, a chart marked in the form of a course and upon which said horses are moved in accordance 20 with the instructions on said cards, and a movable piece representing a winning post,

substantially as and for the purpose hereinbefore set forth.

3. Apparatus for playing race games comprising in combination playing pieces representing horses, a pack of cards bearing indications corresponding to the horses and instructions for the moves to be made by the particular horses indicated some of said cards also bearing penalty and privilege indications simulating the conditions encountered in actual racing such as bumping, 25 swerving, falling, proximity to the rails and the like, some of the cards bearing the instruction "Fall", a chart marked in the form 30 of a course, and movable pieces representing hurdles to be placed on said chart, substantially as and for the purpose hereinbefore set forth.

In testimony whereof I have signed my 40 name to this specification.

WILLIAM JAMES PARSONS.
